DESIGN FOR A FILTER UNIT OR SIMILAR ARTICLE

William B. Pond, West Englewood, and Guild R. Holt, Hohokus, N. J., assignors to Bendix Aviation Corporation, Bendix, N. J., a corporation of Delaware

Application June 3, 1943, Serial No. 110,360

Term of patent 14 years

(Cl. D46—1)

To all whom it may concern:

Be it known that we, William B. Pond and Guild R. Holt, citizens of the United States, residing in West Englewood and Hohokus, respectively, both in the county of Bergen in the State of New Jersey, have invented a new, original, and ornamental Design for a Filter Unit or Similar Article, of which the following is a specification, reference being had to the accompanying drawing, forming part thereof.

In the drawing:

Figure 1 is a perspective view on a slightly

enlarged scale of a filter unit showing our new design.

Figure 2 is a top plan view of the same unit.

Figure 3 is a side elevational view of the unit; and

Figure 4 is an elevational view of the end opposite to that illustrated in Figure 1.

We claim:

The ornamental design for a filter unit or similar article, as shown.
